UNITED STATES PATENT OFFICE.

SIMON ZINN, OF NEW YORK, N. Y.

DESIGN FOR A MATCH-BOX.

SPECIFICATION forming part of Design No. 21,924, dated October 25, 1892.

Application filed August 31, 1892. Serial No. 444,705. Term of patent 7 years.

To all whom it may concern:

Be it known that I, SIMON ZINN, a citizen of the United States, residing at New York, in the county and State of New York, have invented 5 and produced a new and original Design for a Match-Box, of which the following is a specification, reference being had to the accompanying drawing, forming part thereof.

The object of this design is to provide an ornamental and characteristic match-box; and the leading feature thereof resides in a box comprising a base surmounted by the head of a person wearing a cap.

The design is illustrated by the accompanying drawing, in which the figure is a side elevation of the box.

In the drawing the numeral 1 indicates the

base, 2 the representation of the head of a person, and 3 the cap. The cap is shown as provided with a lap 4.

The design provides an ornamental and handsome match-box which presents to the eye a distinguishing and characteristic appearance.

What I claim is—

The design for a match-box, substantially as shown and described.

In testimony whereof I have hereunto set my hand in the presence of two subscribing witnesses.

SIMON ZINN.
